UNITED STATES PATENT OFFICE.

EARL WILLIAM NEWTON, OF CHICAGO, ILLINOIS

LENS FOR AUTOMOBILE-HEADLIGHTS.

1,263,696.

Specification of Letters Patent. Patented Apr. 23, 1918.

Application filed October 12, 1916. Serial No. 125,175.

To all whom it may concern:
Be it known that I, EARL W. NEWTON, a citizen of the United States, and a resident of Chicago, in the county of Cook and State 5 of Illinois, have invented a certain new and useful Improvement in Lenses for Automobile-Headlights, of which the following is a specification.

The present invention relates generally to 10 a lens, and more particularly to a lens adapted to automobile headlights, my object being to provide a highly polished pressed glass lens, the construction of which permits of an effective light diffusion, and especially 15 of economical manufacture of fire-polished ware of this nature.

It is well known that in the manufacture of the usual lens for which purpose it is necessary that the article be highly polished, it 20 is generally necessary in the fire polishing operation to seat the ware at the end of a pipe with molten glass, so that after the fire polishing has been accomplished the article may be "cracked off" the pipe and the rough 25 surfaces ground away and polished.

In accordance with my present improvements I propose to construct a lens in such manner that the above, and comparatively expensive, process of mounting the lens in 30 the fire polishing operation may be dispensed with, the lens, according to my improvements having a portion engageable by a suitable tool to support the article during the fire polishing operation so that immediately after the operation is completed the article may be released without the necessity 35 of grinding and polishing the rough spots such as remain after the article is "cracked off" the pipe in the fire polishing operation 40 ordinarily utilized and as first above described.

My invention further resides in the convenient location of a foot upon the lens 45 adapted to be grasped by a tool in the fire polishing operation as just above mentioned, so located that it may increase the light diffusion or form a support having an adjustable light diffusing member through adjustment of which the diffusion of the light may 50 be effectively controlled.

My invention as thus generally outlined, will be better understood from the following

description thereof, reference being made to the accompanying drawings forming a part of this specification, and wherein:

Figure 1 is a face view of the lens looking at the inner face thereof;

Fig. 2 is a vertical sectional view therethrough taken substantially on line 2—2 of Fig. 1;

Fig. 3 is a face view looking at the outer face of the lens;

Fig. 4 is a side view;

Fig. 5 is an outer face view of a slightly modified form;

Fig. 6 is a side view of the form seen in Fig. 5, partly broken away and in section;

Fig. 7 is a detail perspective view of the adjustable light diffusing shutter, and

Fig. 8 is a detail section through a portion 70 of the prismatic area of the lens.

Referring now to these figures, and more particularly to Figs. 1 to 4 inclusive, my improved lens is, as ordinarily, concavo-convex in shape and indicated at 10, its edge being 75 suitably formed as by means of a flange 11, as seen in dotted lines in Fig. 4, for connection within automobile lamps of well known construction and type, and the inner surface of which is provided with a circular plain or 80 unbroken portion centralized therein as indicated 12 and seen particularly in Figs. 1 and 2, the remainder of the inner surface of the lens having a plurality of radially extending and curved ribs 13 around the central plain portion 12 and constituting the prismatic area which, together with the construction of the lens in certain other respects to be hereinafter described, provides for 85 effective diffusion of the light from the lamp 90 burner in use.

My invention further contemplates the provision of an extended circular foot portion 14 centrally of the lens upon its outer face, the diameter of which is preferably 95 substantially that of the central plain portion 12 of the inner surface, which latter portion and the said foot portion 14 are coaxial with the lens, so that the foot portion which, as seen, projects materially beyond 100 the outer surface of the lens, may be provided, as seen in Figs. 2, 3, and 4, with ribs 15 or otherwise formed to provide for diffusion of light through the center of the

lens, and thus constituting a part of the prismatic light diffusing area of the lens itself.

Thus, by the construction described the lens is not only provided with means securing more effective diffusion of the light, but with a foot portion whereby this is done, which projects beyond the surface of the lens at such a point as that it may be readily 10 grasped by a tool in the fine polishing operation of the article after the latter is pressed to shape so as to render this operation much quicker and more economical than is at present possible.

15 It is to be understood that the foot portion 14 is an integral part of the lens and is pressed to shape with the remaining portions of the lens, and that, in addition to its functions above described, it provides 20 for the support of a metal band 16 therearound, the outer edge of which band projects materially beyond the outer face of the said foot portion, as seen in Figs. 5, 6, and 7, wherein the lens and its foot portion, otherwise similar to the construction 25 shown in Figs. 1 to 4 inclusive, are indicated at 10^a and 14^a respectively.

In the last mentioned form of the invention, as seen in Figs. 5, 6, and 7, the metal band 16 supported around the foot portion 14^a, provides for the use of a hinged circular frame 17, the hinge of which appears at 18 and a curved slotted arm 19 in which a laterally projecting pin 20 of the frame 19 30 works, so that the frame may be secured in adjusted position by a thumb nut 21 threaded on the stem 20 to clampingly engage the arm 19. The frame 17 supports a suitable translucent shutter 22 having a prismatic 35 face, as seen in Figs. 5, 6, and 7, and which, when adjusted to the position shown in Fig. 6 against the outer face of the foot portion 14^a forming light diffusing means for the foot portion the same as the prismatic outer 40 surface 15 thereof of Figs. 1 to 4 inclusive. 45 On the other hand, with the shutter 22 in

use, and raised to a suitable angle, more or less unobstructed rays of light may pass through the central plain portion of the lens.

It is obvious that my improvements provide an economically superior lens, the diffusion of the light through which may be effectively controlled, and a central beam permitted unrestricted passage in certain instances without affecting the normal diffusion of the light in that portion of the prismatic area of the lens around its foot position.

I claim: -

1. An automobile lens of the character described, having a substantially concavo-convex body, and a foot portion projecting beyond the outer face thereof at its center, and a light diffusing shutter adjustably supported on the said foot portion whereby to 60 permit of more or less unobstructed passage of light through the said foot portion.

2. An automobile lens of the character described, having a substantially concavo-convex body, a foot portion projecting beyond the outer face thereof at its center, a band around the said foot portion, and a light diffusing shutter adjustably supported by the said band at the front of the foot portion to partly or wholly cover the latter. 70

3. An automobile lens of the character described, having a substantially concavo-convex body, a foot portion projecting beyond the outer face thereof at its center, a band supported around the foot portion, a 80 light diffusing shutter hinged to the said band, and relatively movable means carried by the said band and the said shutter whereby to secure the latter in selected adjustment with respect to the said foot portion. 85

4. An automobile lens having a centrally projecting foot portion, and a light diffusing shutter mounted on said foot portion.

EARL WILLIAM NEWTON.
